(57) **CLAIM**

We claim the ornamental design for the electronic key card encoder, as shown and described.

DESCRIPTION

FIG. 1 is a perspective view of the invention.

FIG. 2 is a side view of the invention.

FIG. 3 is a front view of the invention.

FIG. 4 is a back view of the invention; and,

FIG. 5 is a top view of the invention.

The broken lines are shown for illustrative purposes only and form no part of the claimed design.
